UNITED STATES PATENT OFFICE

GEORGE F. ALWIN, OF RIPON, WISCONSIN

SNOWPLOW

Application filed April 27, 1929. Serial No. 353,657.

The present invention relates to snow plows and has for its prime object to provide a plow structure which may be mounted on the front end of an automobile or truck frame to project forwardly therefrom.

Another very important object of the invention resides in the provision of a snow plow with means whereby the angle thereof may be adjusted as may be found desirable or necessary for efficient operation.

Another very important object of the invention resides in the provision of a snow plow having a pair of mold boards secured together at their forward ends and diverging rearwardly from each other and connected together by a bracing structure mounted on a frame which includes means for engaging the forward portion of the chassis or frame of an automobile or truck.

20 A still further very important object of the invention resides in the provision of a snow plow of this nature which is simple in its construction, compact and convenient in its arrangement of parts, strong and durable, 25 easy to manipulate, thoroughly efficient and reliable in use, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

25 Figure 1 is a top plan view of the snow plow embodying the features of my invention, Figure 2 is a side elevation thereof,

Figure 3 is a vertical longitudinal section therethrough,

30 Figure 4 is a vertical transverse section taken substantially on the line 4—4 of Figure 2,

Figure 5 is a perspective view of one of the brackets secured to one of the mold boards,

35 Figure 6 is an enlarged detail section taken substantially on the line 6—6 of Figure 3,

Figure 7 is a perspective view of one of the bars secured to the frame, and

40 Figure 8 is a perspective view of one of the lever members.

Referring more in detail to the drawings, it will be seen that the numeral 5 denotes a pair of mold boards, between the forward converging ends of which and extending forwardly therefrom is a divider 4. The 55 divider 4 is made of sheet metal or any other suitable sheet material capable of cutting into the snow and at its inner edge is provided with lateral alternately arranged lips 6, bolted or otherwise secured to the adjacent 60 ends of the mold board 5 for securing said ends together and to the divider 4 as is clearly shown in Figures 1, 3, and 4.

A share 7 is secured at the lower edge of each of the mold boards. The mold boards 65 diverge rearwardly from each other in a V-shaped formation. Angular brackets 8 are mounted on intermediate portions at the inner sides of the mold boards and have braces 9 secured thereto and crossing each other and 70 secured to the rear portions of the mold boards.

The portions of the braces which cross each other are secured together as at 10. L-shaped 75 brackets 11 are secured to the rear portions of the brackets 8 and have pivotally engaged therewith elongated longitudinally extending bars 12 which are connected by an adjustable two-piece cross bar 14 braced in respect to the bars 12 as at 15 and fastened to 80 the bars 12 by means of fastening elements which secure in place toothed segments 16.

Levers 17 are mounted on the bars 12 and have detent structures 18 associated with the toothed segments 16. A pair of bars 19 are 85 secured to the sides of a truck or automobile frame 20 adjacent the forward end thereof to project slightly forwardly therefrom and spacer blocks 21 are preferably interposed between the bars 19 and the frame 20.

Hangers 22 extend downwardly from the rear end of the bars 19 and have L-shaped levers 23 pivotally engaged therewith. The longer legs *a* of the levers are provided with depending arms 24. The short legs *b* rise 95 upwardly and are pivotally connected with rods 25 which in turn are pivotally connected with the levers 17 so that the levers 23 may be rocked by actuating the levers 17.

The juncture of the legs *a* and *b* of the 100

levers 23 are pivotally engaged with the rear ends of the bars 12. A cross rod 26 is engaged with the lower portions of intermediate parts of the shares 5 and rods 27 are pivotally engaged therewith and extend rearwardly and are pivotally engaged with the lower extremities of the arms 24.

From the above detailed description it will be seen that I have devised a plow structure which may be effectively, efficiently, easily and readily mounted on the front end of an automobile frame wherein the shares thereof may be raised or lowered so as to change the angle thereof in respect to the ground to obtain the most efficient operation under varying circumstances. Such change in angle is accomplished by rocking the levers 17 which in turn rock the levers 23 pushing or pulling on the links or rods 27 to swing the shares on the pivots connecting the bars 12 with the bracket 11 and also causing a slight rocking motion on pivot connections 30 between the front extremities of the bars 19 and the rear intermediate portions of the bars 12.

It is thought that the construction, operation, utility and advantages of his invention will now be quite apparent to those skilled in this art without a more detailed description thereof.

The present embodiment of the invention has been disclosed in considerable detail merely for the purposes of exemplification since in actual practice it attains the features of advantage enumerated as desirable in the statement of the invention and the above description.

It will be apparent that changes in the details of construction, in the combination and arrangement of parts may be resorted to without departing from the spirit or scope of the invention as hereinafter claimed or sacrificing any of its advantages.

Having thus described my invention, what I claim as new is:

1. A snow plow of the class described comprising a pair of shares connected together at their forward ends by means of alternately disposed lips, and diverging rearwardly from each other, brackets on the intermediate portions of the inner sides of the shares, and braces secured to said brackets crossing each other and secured to the rear portions of the shares, a cross rod between intermediate portions of the shares, supporting bars, means for attaching the supporting bars on a truck frame, means for pivotally engaging the supporting bars with the brackets, links pivotally connected with the cross rod, means for pulling and pushing the links to rock the shares.

2. A snow plow of the class described comprising a pair of shares connected together at their forward ends by means of alternately disposed lips, and diverging rearwardly from each other, brackets on the intermediate por-

tions of the inner sides of the shares, and braces secured to said brackets crossing each other and secured to the rear portions of the shares, a cross rod between intermediate portions of the shares, supporting bars, means for attaching the supporting bars on a truck frame, means for pivotally engaging the supporting bars with the brackets, links pivotally connected with the cross rod, means for pulling and pushing the links to rock the shares, said means for attaching the supporting bars to the frame comprising a pair of frame bars secured to said frame and having their forward ends pivoted to intermediate portions of the supporting bars, a pair of levers, means for rockably mounting the levers on the frame bars, means for rocking the levers, arms extending from the levers and with which the links are pivotally engaged.

3. A snow plow of the class described comprising a pair of shares connected together at their forward ends by means of alternately disposed lips, and diverging rearwardly from each other, brackets on the intermediate portions of the inner sides of the shares, and braces secured to said brackets crossing each other and secured to the rear portions of the shares, a cross rod between intermediate portions of the shares, supporting bars, means for attaching the supporting bars on a truck frame, means for pivotally engaging the supporting bars with the brackets, links pivotally connected with the cross rod, means for pulling and pushing the links to rock the shares, said means for attaching the supporting bars to the frame comprising a pair of frame bars secured to said frame and having their forward ends pivoted to intermediate portions of the supporting bars, a pair of levers, means for rockably mounting the levers on the frame bars, means for rocking the levers, arms extending from the levers and with which the links are pivotally engaged, and means for pivotally engaging the levers with the rear ends of the supporting bars.

4. A snow plow of the class described comprising a pair of shares converging toward each other at their forward ends, a snow divider disposed vertically between the converging ends of the shares and projecting forwardly thereof, said divider being provided with a plurality of alternately arranged lips, and means for securing the lips to the adjacent ends of the plow shares.

In testimony whereof I affix my signature.

GEORGE F. ALWIN.
